UNITED STATES PATENT OFFICE.

CHARLES LEA, OF MILTON, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed June 5, 1925, Serial No. 35,081. Renewed April 18, 1927.

This invention relates to tube frames of the type used in weaving Axminster carpets or other tufted fabric, and is intended to provide a simple and inexpensive construction of tube frame which shall combine low cost of manufacture with the advantages of that type of tube frames employing a carrier-bar of metal tubing.

Heretofore in the construction of tube frames of the hollow or tubular carrier-bar type it has been the practice to use metal tubing of either the seamless or welded variety to which had been attached devices of various kinds for positioning and holding the yarn-guiding tuft tubes in their operative relation, but as hundreds of tube frames are required for the operation of a single loom the expense of such tubing and the cost of machining it to adapt it to such purpose has been an obstacle to the universal adoption of such tube frames, in spite of their superior merit.

The present invention provides a construction that will greatly reduce the cost of manufacture and at the same time secure the advantages pertaining to the use of carrier-bars of the hollow metallic or tubular type.

To this end the invention comprises, generally speaking, a carrier-bar formed of a longitudinal strip of sheet metal bent along longitudinal lines to form bottom, back and top, and a front wall projecting downwardly from the top wall to form a supporting backing for the intake ends of the tuft tubes, said bottom wall being extended sufficiently beyond the front of the hollow bar to form a projecting ledge provided with transverse tube-receiving apertures, combined with a series of yarn-guiding tuft tubes or quills inserted and supported in said apertures and secured, at their rear or intake ends, to the depending front wall. This and other features of the invention will be particularly described in the following specification and will be defined in the claims hereto annexed.

In the accompanying drawings I have illustrated a preferred form embodying the principles of this invention in which:

Figure 1 is a front elevation showing a sufficient portion of a tube-frame to illustrate the present improvement.

Figure 2 is an end elevation thereof.

Figure 3 is a cross section on the plane $x-x$ of Figure 1, the suspension bracket being removed.

Figure 4 is a cross section on the plane $y-y$ of Figure 1 showing a portion of the suspension bracket in position, as viewed from the inside in elevation.

Figure 5 is a detail showing a plan view of the hollow bar before its bracket-engaging front flanges are turned up.

Figure 6 is a cross sectional view of the same after said flange has been turned up taken through the plane corresponding to $y-y$ of Figure 1.

In the practice of this invention, as illustrated in the drawings, an elongated strip of sheet metal of proper gage to suit service requirements is punched out to form a series of short transverse apertures corresponding to the cross sectional area of the individual yarn-guiding tuft tubes that are to be attached to the carrier-bar.

After such punching operation the strip is rolled up or bent along longitudinal or parallel lines to form bottom wall 1, back 2, top 3 and a depending front wall 4 which preferably is bowed out along its top edge to form a convex rib or ridge 4^a.

In forming or bending the sheet metal strip into this hollow bar, the apertured edge portion forms a forwardly projecting extension 1^a of the bottom wall 1, so that, when the individual tuft tubes 10 are inserted in the apertures 9, their rear or intake ends will have their back surfaces resting against the front wall 4 immediately below the projecting bead or rib 4^a thereof, which forms a supporting backing or anchorage to which the tuft tubes may be secured by any suitable means as by application of drops of solder. As such solder lies beneath the overhanging bead it does not interfere with or catch the yarn entering the tuft tube from the usual yarn-spool which is not herein shown.

To suspend the carrier-bar and support the yarn-spool the ear or suspension bracket 12 is provided. This has an upward extension 12^a forming a spool-supporting bearing ear and an outward upwardly projecting extension 12^b, forming a chain-penetrating prong adapted to pass into the links of the usual carrier-bar. There is also provided a yielding hook latch 13 whose lower end is bent into a loop to embrace a transverse fulcral pin 14 located inside the end of the hollow bar and kept against endwise displacement by the front and back walls of

the hollow bar. A spring 15, interposed between the latch and the hanger 12, normally presses the latch into hooked engagement with the carrier-chain while allowing it to yield under the external pressure of the transfer clutch or mechanism to be disengaged from the carrier chain. The suspension bracket is provided with an inwardly projecting bottom wing 12^c and a parallel top wing 12^d which form attaching wings or members which are rigidly secured to the bottom and top walls, respectively, by suitable means such as fastening screws 20, and which preferably engage the adjacent front and back portions for positioning support.

According to the usual practice, the row of tuft tubes terminates some distance from the end of the carrier-bar in order to allow the transfer clutch to overlap the front and back faces of the bar, and at these points the forwardly projecting portion of the bottom wall is turned upwardly toward the depending front wall, as shown at 1^b, and forms an up-standing flange or lip overhanging the front edge of the bottom wing 12^c which it snugly engages, thus forming guiding or positioning means for the bottom wing, just as the top wing extends across the interior from back to front to similarly guide and support against torsional displacement of the carrier-bar in relation to the hanger, and to that extent relieves the attaching screws from unnecessary strains of this character.

35. What I claim is:

1. In a tube frame the combination of a carrier-bar comprising an elongated strip of sheet metal bent longitudinally to form bottom, back and top walls, and a front wall projecting downwardly from the top wall to form a backing to which the yarn-guiding tuft tubes are secured, the bottom wall being extended forwardly beyond the plane of the front wall and being provided 45 with a series of parallel apertures in its forwardly projecting portion and a series of yarn-guiding tuft tubes inserted in said apertures and secured at their upper or intake ends to said downwardly projecting front wall, substantially as described.

2. A tube frame embracing in its construction a metallic sheet bent longitudinally to form a hollow bar of prismatic form, the bottom of which is extended out beyond the front wall and separated therefrom by a longitudinal intervening space, and a longitudinal series of parallel tuft tubes inserted in apertures formed in the forwardly projecting edge portion of the

bottom and having their intake ends extending across said intervening space and secured to the front wall which extends downwardly behind them to afford a backing support therefor, substantially as described. 60

3. A tube frame embracing in its construction a hollow bar of sheet metal bent longitudinally to form bottom, back and top walls and a front wall depending from the forward edge of the top and formed with an outwardly projecting rib, the bottom wall projecting forwardly of the plane of the front wall and having such projecting portion provided with transverse tube-receiving apertures, and a series of parallel tuft tubes inserted in said apertures with 75 the backs of their intake ends secured to said front wall beneath the overhanging rib of said front wall, substantially as described.

4. A carrier bar for a tube frame comprising an elongated strip of sheet metal bent along longitudinal lines to form a hollow prismatic bar whose bottom member intermediate of its ends projects beyond the front of the bar and is provided with 80 a row of tube-receiving apertures in such projecting portion, each end portion of the projecting bottom being turned upwardly to overlap the attaching member of a suspension bracket inserted in the end of the 90 hollow bar, substantially as described.

5. A carrier bar for a tube frame comprising an elongated strip of sheet metal bent longitudinally to form a hollow prismatic bar whose bottom projects forwardly 95 of the front and is provided with a row of transverse tube-receiving slots in said projecting portion, the front wall extending down from the top part way to the bottom to form a longitudinal backing behind tuft 100 tubes inserted in said apertures and being bowed outwardly above said backing portion to form an overhang, substantially as described.

6. In a tube frame the combination of 105 a tubular carrier-bar comprising a strip of sheet metal bent into tubular form with its front wall extending down part way to the bottom leaving a longitudinal gap between the front wall and the bottom, and a row 110 of tuft tubes secured to the front wall and to the bottom and serving to form a connecting bridge over said gap with their delivery ends projecting below the bottom in spaced relation, substantially as described. 115

In witness whereof, I have subscribed the above specification,

CHARLES LEA.
